FRED H. DANIELS AND AXEL F. BACKLIN, OF WORCESTER, MASSACHUSETTS, ASSIGNEES TO THE AMERICAN STEEL & WIRE COMPANY OF NEW JERSEY, OF HOBOKEN, NEW JERSEY, A CORPORATION OF NEW JERSEY.

APPARATUS FOR HANDLING METAL BARS.

1,021,582.

Specification of Letters Patent. Patented Mar. 26, 1912.

Application filed October 30, 1908. Serial No. 460,361.

To all whom it may concern:

Be it known that we, FRED H. DANIELS and AXEL F. BACKLIN, both of Worcester, Worcester county, Massachusetts, have invented a new and useful Apparatus for Handling Metal Bars, of which the following is a full, clear, and exact description, reference being had to the accompanying drawings, forming part of this specification,

10 in which—

Figure 1 is a plan view showing a portion of bar-handling apparatus constructed and arranged in accordance with our invention; Fig. 2 is a sectional elevation of the same taken on the line II—II of Fig. 1, showing one position assumed by the moving parts in handling metal bars; Fig. 3 is a view similar to Fig. 2 showing the parts in another position assumed during the transfer 20 movement; Fig. 4 is a detail in side elevation; and Fig. 5 is a detail sectional end elevation of the reciprocating bars, showing the positions assumed by the ratchet pawls in actuating the ratchet wheels employed 25 for rotating the shafts and star wheels forming the conveyer; Fig. 6 is a detail view showing a modified form of star wheel.

Our invention relates to apparatus for handling metal bars and like materials 30 manufactured in rolling mills, and the object of the invention is to provide improved means for handling such materials, particularly after the completion of the rolling operation during the interval in which the 35 hot materials are being cooled sufficiently to permit of their being handled without liability of damage to the materials or injury to the operatives.

The invention consists in providing bar 40 handling apparatus of improved construction, which is arranged to handle the products of rolling mills and to transfer such material laterally across the width of the apparatus from a roller delivery table located alongside the apparatus to a roller receiving table located on the opposite side of the apparatus, upon which the materials are deposited and by which they are carried to the shears or other point of disposal.

The invention further consists in providing apparatus which is adapted to handle such materials while they are being cooled from the hot state in which they are fin-

ished by the reducing rolls of rolling mills, 55 so as to prevent damage or injury to the materials or distortion of the shapes while being so handled and at the same time providing sufficient storage capacity to permit of the gradual cooling of the materials, 60 while being supported upon the apparatus and prevent delays in the operation of the mill.

In the drawings, 2 represents the feed rollers of the delivery table, upon which 65 the materials being handled are delivered lengthwise alongside the transverse conveyer, in position to be transferred from the rollers to the conveyer, and 3 the feed rollers of the receiving table, located on the 70 opposite side of the conveyer and upon which the materials are received and are carried away from the conveyer. The rollers 2 and 3 forming the roller tables are positively driven through bevel gears 4 and 75 5 and line shafts 6 and 7 by the respective driving motors (not shown) which are connected to the line shafts.

Located between the feed tables formed by the sets of rollers 2 and of rollers 3 is a 80 series of sets of horizontally extending rotary shafts 8, the shafts in each set being arranged in substantially parallel vertical planes. The axes of the several sets of shafts 8 are arranged in endwise alignment 85 with those of the adjoining sets, when more than one set is employed the number of sets varying with the length of the shafts and the total length required for the apparatus, in order to support the full length of the 90 bars or other materials being handled by the apparatus, in the drawings one complete set and portions of two adjoining sets being shown. Each of the shafts 8 is provided with two or more star wheels 9 having a plurality of radially extending projections or teeth 9a, the number of wheels necessary on each shaft depending upon the length and flexibility of the materials being transferred by the apparatus and the 100 distance necessary between the supports in order to prevent distortion or damage to such materials.

The wheels 9 on the shafts 8 are staggered with relation to those on adjacent 105 shafts and the shafts are spaced apart so that the teeth 9a on each shaft will overlap those on the adjoining shafts and will lift

and transfer the bars from the teeth on the shaft on its one side to those on the shaft on its other side. The rotatable shafts 8 have reduced end portions 8^a which extend 5 into suitable bearings provided for that purpose and each of the star wheel shafts is shown provided with ratchet wheels 10 and 11 by means of which the shafts are actuated and the star wheels are caused to turn 10 and are held so as to prevent their backward movement by the weight of the materials being transferred.

Mounted in suitable bearings below the horizontal shafts 8 so as to extend lengthwise horizontally and at right angles to the axes of the shafts 8 are the reciprocating bars 12 and 13 and pivotally mounted on these bars are the ratchet pawls 14 and 15 by means of which the ratchet wheels are 15 operated, one pawl being provided for each ratchet wheel. Lifting arms 16 are secured upon the lifting shafts 17 with their outer ends extending between the rollers 2 so as to engage with and transfer the bars laterally 20 from the rollers 2 to the star wheels 9 when the shaft 17 is rocked to lift the arms, and slides 18 which extend between the rollers 3 are arranged to carry the bars deposited 25 upon the slides by the star wheels to the 30 rollers 3.

The reciprocating bars 12 and 13 are connected by means of reach rods or links 19, 20 to one side of the oppositely projecting lever arms 21 and 22 which are secured on 25 the rocking shaft 23 by means of which the star wheel actuating mechanism is actuated, these bars being arranged to move in opposite directions. The lifting shafts 17 carrying the rocking lifting arms 16 are also connected to and actuated by the reciprocating 30 bars 12 through the lever arms 24 on the shaft 17 and the links 25. The rocking shaft 23 is connected to and operated through the reach rod 26 by the crank 27 which in turn 35 is connected to a suitable driving motor (not shown).

In the operation of our improved apparatus, the bars are delivered lengthwise by the rollers 2 until they are alongside the 40 transverse conveyer formed by the star wheels in position to be transferred to the star wheels. The crank 27 is then caused to actuate the shaft 23. As this shaft is rocked by the crank, the bars 12 and 13 are reciprocated in opposite directions. When the bar 45 12 is moved from right to left the points 14^a of the pawls 14 engage with the teeth in the ratchet wheels 10 which are on the shafts 8 and rotate these shafts through a part of a 50 revolution. The bar 12 is then caused to travel in the opposite direction, and the direction of movement for the bar 13 is also 55 changed. By this movement, the points 15^a of the pawls 15 engage with the teeth of the 60 ratchet wheels 11 also secured on the shafts 65

8 and rotate these shafts through another part of a revolution. These operations are repeated intermittently so that the star wheels 9 are caused to rotate by an intermittent movement, a series of such steps being necessary to rotate the shaft and wheel throughout one revolution. The reciprocating bars 12 and 13, by moving in opposite directions also serve to lock the star wheels against their backward movement and prevent the shafts 8 from rotating in opposite directions by reason of the weight of the materials supported upon and being transferred by the apparatus. By the opposite and intermittent movements of the bars 12 70 and 13, one of the pawls 14 is always engaged with the teeth in one of the ratchet wheels 10 and 11 which are mounted upon the shafts 8, in this way compelling the star wheels to rotate always in the same direction. Each back and forth movement of the bars 12 causes the lifting arms 16 to be lowered from the position shown in Fig. 2 to that shown in Fig. 3, and to be again raised into the position shown by Fig. 2, this 75 lifting movement raising any bars which may be in position on the rollers 2 of the delivery table, and causing them to be shifted laterally from the feed rollers to one of the series of points on the star wheels as is 80 shown in Fig. 3. The step by step movement of the star wheels causes the bar to be advanced from one row or line of wheels to the next adjacent row of wheels, and finally to reach the inclined supports 18, which are 85 located at the opposite or delivery side of the apparatus, from this point the bars being transferred by gravity to the rollers 3 of the receiving table.

The above steps are carried out so as to 90 transfer the bars or other materials from the rollers forming the table 2 to the rollers 3 forming the receiving table, and as the bars are slowly transferred across the width of the conveyer between these points, they become cooled to a sufficient extent that they 95 can be handled without danger of damage to the bars or injury to the operatives.

The advantages of our invention are many, and will be appreciated by those skilled in 100 the art. By the arrangement of the substantially parallel rows of star wheels the materials are supported at frequent intervals in their length, and distortion or bending of flexible materials which this apparatus 105 is designed to handle, will be prevented during their movement in the hot state in which they are delivered from the rolling mill. The apparatus is simple, and can be easily kept in repair.

Modifications in the construction and arrangement of the parts may be made without departing from our invention. The feed tables may be located at different elevations with the conveyer mechanism in- 110 115 120 125 130

clined from the level of one table to that of the other, instead of being horizontal and on substantially the same level.

The size and shape of the star wheels may 5 be changed and the number of wheels on each wheel shaft may be varied. The wheels may be formed integral on the shaft, as shown, or may be keyed or otherwise secured thereto, as is desired. But one set of reciprocating bars with its pawls may be employed when desired instead of the two sets which are alternately in operative engagement with the ratchet wheels as shown in the drawings, in which case a pawl or 10 equivalent device is provided to hold the shafts and star wheels from rotation backwardly or in opposite directions.

Instead of employing ratchet wheels and pawls with reciprocating bars for intermittently rotating the star wheels, as is shown in the drawings, spur gearing or worm gearing, or any equivalent device for rotating the star wheels may be employed. The size and number of shafts may be varied so as to 25 form transfer apparatus of any desired width and length. The form of the projections on the star wheels may be changed to suit materials of different cross section, and many other changes may be made without departing from our invention.

We claim:—

1. Apparatus for handling metal bars, comprising a series of sets of toothed wheels, the teeth of adjacent sets of wheels overlapping and having edge portions arranged to lift and transfer the bars sidewise from one side to those on the opposite side when said wheels are rotated, and means including a ratchet and pawl for rotating the wheels; 35 substantially as described.

2. Apparatus for handling metal bars, comprising a conveyer having a series of sets of toothed wheels, with the teeth of adjacent sets of wheels overlapping, the teeth having 40 edge portions arranged to engage with and positively move bars supported thereon laterally across the width of the apparatus

from series to series when the wheels are actuated, and means for intermittently actuating the wheels to transfer the bars; substantially as described.

3. Apparatus for handling metal bars, comprising a roller delivery table arranged to deliver bars lengthwise thereon, and having means for actuating the table, a conveyer having a series of sets of toothed wheels with the teeth in one set overlapping those in its adjacent set, and having means for actuating said wheels, and mechanism arranged to simultaneously transfer the bars 55 from the table to the conveyer and on the conveyer when said conveyer wheels are actuated; substantially as described.

4. Apparatus for handling metal bars comprising a series of sets of toothed wheels 60 having the teeth of adjacent wheels overlapping, and arranged to transfer sidewise bars supported thereon when the wheels are rotated, and means including a ratchet and pawl for rotating the wheels; said means being arranged to prevent backward movement of said wheels; substantially as described.

5. Apparatus for handling metal bars comprising a conveyer having a series of 65 sets of toothed wheels with the teeth of the adjacent sets overlapping and arranged to move bars supported thereon sidewise across the width of the apparatus when the wheels are actuated, and means for intermittently 70 actuating the wheels to transfer the bars, said actuating means being adapted to alternately hold the sets of wheels to prevent backward movement thereof and rotate the wheels to transfer the bars; substantially as 75 described.

In testimony whereof, we have hereunto set our hands.
